UNITED STATES PATENT OFFICE.

HUGO B. GRANT, OF CHICAGO, ILLINOIS.

INTERNAL-COMBUSTION ENGINE.

1,409,093.

Specification of Letters Patent.

Patented Mar. 7, 1922.

Application filed October 26, 1920. Serial No. 419,651.

To all whom it may concern:

Be it known that I, HUGO B. GRANT, a citizen of the United States, residing at Chicago, in the county of Cook and State of

5 Illinois, have invented new and useful Improvements in Internal-Combustion Engines, of which the following is a specification.

This invention relates to internal-combustion engines of the two-cycle type, and its 10 object is to provide a very simple and highly efficient engine of this type, and one in which the fuel charges are forcibly injected into the cylinder, the motive power for such fuel injection being derived from an air 15 pump driven by the engine.

The invention also has for its object to provide a novel and improved expedient for heating the fuel charges to complete the vaporization thereof, and furthermore, to 20 provide for a thorough scavenging of the engine cylinder prior to the injection of the new fuel charges.

Other objects and advantages of the invention will be pointed out in the detailed 25 description appearing hereinafter.

In order that the invention may be better understood, reference is had to the accompanying drawings forming a part of this specification, and in said drawings.

30 Figure 1 is a vertical sectional view of the engine.

Figure 2 is a horizontal section on the line 2—2 of Fig. 1;

Figure 3 is an elevation of the piston;

35 Figure 4 is an enlarged section on the line 4—4 of Fig. 1 showing the throttle valve open, and

Figure 5 is a view similar to Fig. 4 showing the throttle valve closed.

40 Referring specifically to the drawings, 10 denotes the cylinder of the engine, the same being shown as cast with the upper section 11 of a crank case having a detachable lower section 12. The crank shaft 13 extends 45 through the crank case, the latter having suitable bearings supporting said shaft. The crank case is also shown with laterally extending supporting arms 14. The drawings disclose a single cylinder engine, but it

50 will be understood that the engine may be provided with any number of such. The crank case is provided with the usual breather and

oil filler pipe 15. The cylinder 10 has a detachable head 16 carrying a spark plug 17 for igniting the fuel charges.

55

A reciprocating piston 18 works in the cylinder 10 and is joined by a connecting rod 19 to the crank shaft 13 for driving the latter. The piston is of the usual trunk type carrying a wrist pin 20 for connection of the 60 rod 19 therewith. The top of the piston is formed with a chamber 21 which opens into the explosion chamber of the cylinder 10 and has its side wall in sliding contact therewith, and provided with perforations 22 forming 65 exhaust outlet parts, the same being located at the bottom of the piston chamber and spaced from the open top thereof.

In the side wall of the cylinder 10 is a fuel inlet or admission port 23, and below or 70 ahead of the same the cylinder sidewall has a plurality of exhaust ports 24 opening into an annular chamber 25 formed in the cylinder wall and having two outlets 26 to which is adapted to be connected the usual exhaust 75 manifold.

The side wall of the cylinder 10 also has an annular water jacket space 27, and surrounding the latter concentrically is a fuel-heating chamber 28 which is in communication with 80 the port 23. The chamber 28 has an inlet portion 29 opening through the side wall of the cylinder 10 for connection with a charge-forming device.

In the port 23 is mounted a throttle valve 85 for controlling the volume of fuel admitted to the cylinder 10 and thus regulating the speed and power of the engine. This valve is a hollow turning plug 30 having a side inlet port 31 adapted to open into the chamber 28. The plug 30 extends to the outside of the cylinder 10 and is here fitted with a lever arm 32 for operation. The fuel supply can be completely shut off by turning the valve plug 30 until its port 31 no longer 90 opens into the chamber 28. The valve plug 30 is held in place by a retaining plate 33 bolted to the cylinder 10.

The charge-forming device hereinbefore referred to consists of a casing 34 which is 100 so connected to the cylinder 10 that a passage 35 in said casing is in communication with the inlet 29 of the fuel-heating chamber 28. Into the passage 35 extends a fuel nozzle 36

and arranged in said passage to discharge across the mouth of said nozzle, is an air nozzle 37 connected by a conduit 38 to an air-pump 39 driven by the crank shaft 13 through any suitable means, such as a sprocket-and-chain gearing. The pump 39 is supported by one of the crank case supporting arms 14. The passage 35 also opens to the external atmosphere, and it is here fitted with a valve 40 of the ordinary butterfly type for controlling the amount of air entering the passage. The nozzle 36 is provided with a needle valve 36a for controlling the volume of fuel discharged.

15 The charge-forming device hereinbefore described operates similar to an atomizer to blow or forcibly inject a mixture of air and liquid fuel into the chamber 28, and when the port 23 is uncovered by the piston 18 a fuel charge is forcibly injected into the cylinder 10. At this time, the piston ports 22 are registering with the exhaust ports 24 and the spent gases are escaping into the chamber 25, passing out of the same through 25 the outlets 26 thereof. On the return stroke of the piston the newly admitted charge is compressed and then fired to obtain the working stroke of the piston. At the end of the working stroke the exhaust of the spent 30 gases and the admission of a fresh fuel charge takes place. The engine therefore operates on a two-cycle, a power impulse being obtained at every revolution of the crank shaft.

35 It will be noted that the ports 22 are not in the same plane as the inlet port 23 and that the wall of the chamber 21 has two diametrically imperforate portions 41 one of which coincides with the location of the port 23 so as to slide across the same. The port 23 is not uncovered by the part 41 until the exhaust gases have passed out of the cylinder 10 through the ports 22 and 24, and hence the incoming fresh fuel charge is 45 not fouled or prematurely ignited by any spent gases remaining in the cylinder. The cylinder is also completely scavenged by the forcible injection of the fresh fuel charges.

The charge forming device delivers the 50 liquid fuel into the chamber 28 in the form of a fine mist which is completely and quickly vaporized in said chamber, due to the heat derived from the cylinder wall and the water jacket 27, as well as the wall of 55 the exhaust chamber 25, said wall also serving as strengthening walls for the entire cylinder casting. The engine does not rely on suction to draw fuel into the cylinder, but the fuel charges are forcibly injected, 60 as a pressure is produced by the air jet 37. The cylinder is therefore filled to its full capacity, resulting in a maximum power.

By providing the piston 18 with the two diametrically opposite imperforate portions 65 41, no particular care is necessary when in-

serting the piston into the cylinder 10, because it may be placed to position either one of said parts to line up with the port 23. The piston is fitted with rings 42 which are so located that they do not pass over the cylinder ports 24, and hence they are not in danger of getting caught and breaking.

The engine has no valves and no cam shaft, its only moving parts being the piston, the connecting rod and the crank shaft, and hence the construction is simple, and all complicated parts liable to get out of order have been eliminated. More horse power per unit of weight is obtained because of the absence of such mechanism as valves, valve 80 springs, valve guides, lifters, cam shafts, etc., and this makes the engine much lighter than a four-cycle engine of equal piston displacement.

I claim:

1. In an internal-combustion engine, a cylinder having inlet and exhaust ports, and a reciprocating piston in the cylinder having a chambered top provided with side ports, said top uncovering the inlet port, and the side ports registering with the exhaust ports at the end of the firing stroke of the piston.

2. In an internal-combustion engine, a cylinder having inlet and exhaust ports, and a reciprocating piston in the cylinder having a chambered top provided with side ports, said top uncovering the inlet port, and the side ports registering with the exhaust ports at the end of the firing stroke of the 100 piston, the exhaust ports being spaced from the inlet port in the direction of the length of the cylinder.

3. In an internal-combustion engine, a cylinder having inlet and exhaust ports, and a ported reciprocating piston in the cylinder, the top of the piston uncovering the inlet port, and the piston ports registering with the exhaust ports at the end of the firing stroke of the piston.

4. In an internal-combustion engine, a cylinder having inlet and exhaust ports, and a ported reciprocating piston in the cylinder, the top of the piston uncovering the inlet port, and the piston ports registering with the exhaust ports at the end of the firing stroke of the piston, the exhaust ports being spaced from the inlet port in the direction of the length of the cylinder.

5. In an internal-combustion engine, a 120 cylinder having inlet and exhaust ports, a reciprocating piston in the cylinder having a chambered top provided with side ports, said top uncovering the inlet port, and the said ports registering with the exhaust ports 125 at the end of the firing stroke of the piston, and means for forcibly injecting a fuel charge into the cylinder when the inlet port is uncovered by the piston.

6. In an internal-combustion engine, a 130

- cylinder having inlet and exhaust ports, a reciprocatory piston in the cylinder having a chambered top provided with side ports, said top uncovering the inlet port, and the 5 side ports registering with the exhaust ports at the end of the firing stroke of the piston, the exhaust ports being spaced from the inlet port in the direction of the length of the cylinder, and means for forcibly injecting 10 a fuel charge into the cylinder when the inlet port is uncovered by the piston.
7. In an internal-combustion engine, a cylinder having inlet and exhaust ports, a ported reciprocatory piston in the cylinder, 15 the top of the piston uncovering the inlet port, and the piston ports registering with the exhaust ports at the end of the firing stroke of the piston and means for forcibly injecting a fuel charge into the cylinder 20 when the inlet port is uncovered by the piston.
8. In an internal-combustion engine, a cylinder having inlet and exhaust ports, a ported reciprocatory piston in the cylinder, 25 the top of the piston uncovering the inlet port, and the piston ports registering with the exhaust ports at the end of the firing stroke of the piston, the exhaust ports being spaced from the inlet port in the direction 30 of the length of the cylinder, and means for forcibly injecting a fuel charge into the cylinder when the inlet port is uncovered by the piston.
9. In an internal-combustion engine, a cylinder having inlet and exhaust ports, a reciprocatory piston in the cylinder having a chambered top provided with side ports, 35 said top uncovering the inlet port, and the side ports registering with the exhaust ports 40 at the end of the firing stroke of the piston, means for forcibly injecting a fuel charge into the cylinder when the inlet port is uncovered by the piston, and a throttle controlling the volume of fuel injected into the 45 cylinder.
10. In an internal-combustion engine, a cylinder having inlet and exhaust ports, a reciprocatory piston in the cylinder having a chambered top provided with side ports, 50 said top uncovering the inlet port, and the side ports registering with the exhaust ports at the end of the firing stroke of the piston, the exhaust ports being spaced from the inlet port in the direction of the length 55 of the cylinder, means for forcibly injecting a fuel charge into the cylinder when the inlet port is uncovered by the piston, and
- a throttle controlling the volume of the fuel injected into the cylinder.
11. In an internal combustion engine, a cylinder having inlet and exhaust ports, a ported reciprocatory piston in the cylinder, the top of the piston uncovering the inlet port, and the piston ports registering with the exhaust ports at the end of the firing 60 stroke of the piston, means for forcibly injecting a fuel charge into the cylinder when the inlet port is uncovered by the piston, and a throttle controlling the volume of fuel injected into the cylinder. 65
12. In an internal combustion engine, a cylinder having inlet and exhaust ports, a ported reciprocatory piston in the cylinder, the top of the piston uncovering the inlet port, and the piston ports registering with the exhaust ports at the end of the firing 70 stroke of the piston, the exhaust ports being located in the cylinder ahead of the inlet port, means for forcibly injecting a fuel charge into the cylinder when the inlet port is uncovered by the piston, and a throttle controlling the volume of fuel injected into the cylinder. 75
13. In an internal combustion engine, a cylinder having inlet and exhaust ports, and a reciprocatory piston in the cylinder having a chambered top the sides of which are perforated to form side ports, said top uncovering the inlet port, and the aforesaid side ports registering with the exhaust 80 ports at the end of the firing stroke of the piston, the imperforate portion of the chambered piston top coinciding with the location of the cylinder inlet port. 85
14. In an internal-combustion engine, a cylinder having a combustion chamber and a fuel inlet port opening into said chamber, and the side wall of the cylinder having a fuel heating jacket which is in direct communication with the aforesaid inlet port, and has a fuel inlet. 90
15. In an internal combustion engine, a cylinder having a combustion chamber and a fuel inlet port opening into said chamber, and the side wall of the cylinder having a fuel heating jacket which is in direct communication with the aforesaid inlet port, and has a fuel inlet, the side wall of the cylinder also having an internal exhaust-receiving chamber adjacent to one end of the fuel-heating jacket and concentric therewith. 105

In testimony whereof I affix my signature.

HUGO B. GRANT.
